UNITED STATES PATENT OFFICE

2,618,003

TOOTHBRUSH

William G. Robey, Grafton, W. Va.

Application April 5, 1948, Serial No. 19,012

1 Claim. (Cl. 15—176)

1

This invention relates to toothbrushes and the like.

An object of this invention is to provide a toothbrush having a handle adapted for permanent use and having means for removably mounting a toothbrush in the head end thereof, so that the same may be readily renewed when worn or easily removed for cleaning so as to maintain the brush in a sanitary condition.

Another object of the invention is to provide a permanent toothbrush holder and handle which may be made of any suitable material such as plastic, metal, ivory, etc., and the brush proper of similar material in which the bristles which may also be of plastic are embedded and the head of the handle provided with an opening, recess or socket having means to removably receive and hold the toothbrush head so that the latter will be properly held in position for use, but may be readily removed by inserting a fingernail or any sharp object to lift the brush out of the holder, thereby forming a permanent instrument in which a new brush may be inserted when needed at small cost.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a side elevation of a toothbrush constructed in accordance with one embodiment of the invention.

Figure 2 is an enlarged fragmentary bottom plan of the head end of the brush.

Figure 3 is a longitudinal section taken on the line 3—3 of Figure 2.

Figure 4 is a transverse section taken on the line 4—4 of Figure 3.

Figure 5 is a view similar to Figure 2 of a modification and with the brush head proper partly in position as when being inserted or removed.

Figure 6 is a longitudinal section on the line 6—6 of Figure 5.

Figure 7 is a transverse section taken on the line 7—7 of Figure 6.

Referring to the drawing in detail, the brush is shown as comprising a handle 10 of any suitable type and of plastic, metal, ivory or other suitable material. It is shown provided with a tapered portion 11 merging into a reduced shank 12 and 55

an oppositely tapered or enlarged portion 13 forming a head 14 of substantially enlarged rectangular shape and plan and suitable thickness substantially corresponding to that of the shank or slightly greater. The bristles are indicated at 15, and may be of tufts of suitable material or even plastic, and embedded in a head proper 16 adapted to be removably mounted in an opening, socket or recess 17 of rectangular form provided in the under side of the head 14.

The recess 17 forms a top wall 18, side walls 19, a rear wall 20 and a front wall 21. Embedded or otherwise secured in the top wall 18 is a suitable fastening means such as a resilient spring metal strip 22 disposed centrally and longitudinally thereof in the form shown and having right angularly bent ends formed with spring catches or jaws 23 bent in opposite directions toward each other after passing into the recess 17 through the inner thickness of the wall 18 in spaced relation to the end walls 20 and 21. As shown, these catches or jaws are bent convexly inwardly with their extremities bent outwardly and the brush head proper 16 is adapted to be inserted in the opening or socket 17 for detachable engagement with the catches 23 at the ends thereof and with its bottom face substantially flush with the open side of the head 14. At each end, the recess 17 is provided with a central reduced recess or groove 24 into which the spring catches or snap jaws 23 are adapted to project so that a fingernail or any sharp instrument may be inserted to disengage the catches and permit removal of the brush head.

Preferably, each end of the head 16 is provided with a transverse recess or seat 25 shown of concave form into which the catches 23 are adapted to engage so as to removably hold the brush head in position by resilient or frictional engagement of the catches or snap springs therein or otherwise, as it is thought will be apparent. The transverse grooves or recesses 25 form transverse projecting ribs or engaging portions 26 for insertion of the fingernail or an instrument therebeneath to easily remove the brush head and bristles from engaged position. The inner end is also preferably extended at an angle or inclined toward the rear and open side of the head 14 at the recess 17 and is provided with an additional transverse groove or recess 27 forming a projecting rib or lip 28 adjacent a groove or recess 29 in the bottom face of the portion 13 in the rear wall 20 at the open side of the recess adjacent the rib or lip 28 to facilitate insertion of a fingernail or instrument for raising the brush

head 16 to easily remove the same from its socket or recess and the adjacent angularly inclined or beveled end of the brush head 16 prevents binding of the latter. Of course, the device may also be removed from the opposite end or only one of the recesses 24 need communicate or extend through the lower face of the head 14, or be provided to extend from recess 17.

It will thus be seen that the toothbrush proper may be readily inserted in the socket, opening or seat of the handle, the latter forming a permanent part of the instrument in which a new brush may be inserted when needed at small cost.

In the form of the invention shown in Figures 5, 6 and 7, the construction is generally the same and corresponding parts are similarly numbered, except that the opening or recess 17 is open at the front end as shown at 29 and slidably receives the brush head proper 16 carrying the bristles 15. For this purpose, the side walls 19 are provided on their inner faces with grooves 30 extending longitudinally for slidable engagement by ribs 31 projecting out from the opposite sides of the head 16 at a suitable point between the bottom and open side of the recess 17 so as to 10 frictionally and detachably retain the brush in position. The part of the brush head 16 in which the bristles are embedded may be separate from the part which engages in the recess 17 or integral therewith and if separate, may be fused, cemented or otherwise secured together. The opposite walls 18 may be contracted slightly less than the width of the head 16 or made resilient so as to give proper frictional engagement to 15 detachably hold the head 16 in position. Where the head 14 forming a part of the handle is open, this end is adapted to be closed by a transverse wall 32 formed at the front of the head 16 as a flange projecting from the sides as indicated at 33 and at the top as indicated at 34 so as to fit against the front ends of the walls 18 and 19 and close the opening 29. Some cement or adhesive may be provided to temporarily augment the attachment of the removable brush head so as not to interfere with its convenient removal when replacing the brush or for cleaning purposes to maintain the sanitary condition thereof, or resilient or spring catches formed by or separate from walls 19, or even 18 or 20, provided to detachably hold brush head 14 in position.

A cap 35 may be applied over the shank and tapered front portion of the handle 10 and brush head 14-15, the same having a tubular portion over the shank frictionally or threadably engaged detachably on the handle 10 near the shank 12 and tapered portion 11 as indicated at 36. As

shown, the handle 10 is bulged and has external threads on which may be threaded internal threads at the open inner end of the cap which is large enough for the cap to go over the brush. The closed front end of the cap is also enlarged as at 37 to accommodate the brush head and allow the bristles to straighten out after giving when cap is shoved over them.

I claim:

In a toothbrush, a relatively wide head formed with an elongated recess opening through one face thereof, an elongated bar embedded in said head in the bottom of said recess, arcuate catch members extending from the ends of said bar and projecting into said recess adjacent the opposite ends of the latter, and a brush formed of a back and bristles carried by said back, said back removably seating in said recess and formed with transverse grooves in the opposite ends thereof within which said catch members engage, said head having a concave finger recess adjacent one end of said first named recess, said back having a second transverse channel at one end thereof whereby a finger extended into said finger recess may release said brush from said catch members.

WILLIAM G. ROBEY.
